US0D1054786S

(12) **United States Design Patent** (10) **Patent No.:** **US D1,054,786 S**
(45) **Date of Patent:** **** Dec. 24, 2024**

(54) **TUMBLER**

(71) Applicant: **Hydrojug, Inc.**, Ogden, UT (US)

(72) Inventor: **Josh Kumpf**, Layton, UT (US)

(73) Assignee: **HYDROJUG, INC.**, Ogden, UT (US)

(**) Term: **15 Years**

(21) Appl. No.: **29/830,126**

(22) Filed: **Mar. 10, 2022**

(51) LOC (14) Cl. **07-01**

(52) U.S. Cl.

USPC **D7/511**; D7/300.1

(57) **CLAIM**

The ornamental design for a tumbler as shown and described.

DESCRIPTION

FIG. 1 is a perspective view of the tumbler;

FIG. 2 is a first side view thereof;

FIG. 3 is a second side view thereof;

FIG. 4 is a third side view thereof;

FIG. 5 is a fourth side view thereof;

FIG. 6 is a top view thereof;

FIG. 7 is a bottom view thereof; and,

FIG. 8 is a perspective alternate/exploded view thereof.

The dashed lines depict portions of the tumbler that form no part of the claimed design.

1 Claim, 7 Drawing Sheets
